ABSTRACT: An improvement in rapid reversal color photoprocessing is disclosed for removing excess free aldehyde compounds from photoprocessing solutions by contacting the aldehyde compounds with bisulfite ion.

METHOD FOR REMOVING EXCESS ALDEHYDES

BACKGROUND OF THE INVENTION

1. Field of the Invention

This invention relates to the removal of excess free aldehyde compounds from rapid reversal color photoprocessing solutions.

2. Description of the Prior Art

Aldehyde compounds are often present in photoprocessing solutions. For example, in the rapid reversal processing of color films, aldehydes are used to harden the sensitive hydrophilic colloid layers subsequent to first development to allow further processing at elevated temperatures without concomitant emulsion damage. Rapid reversal color processes are described in more detail in my copending application: U.S. Ser. No. 699,576, filed Jan. 22, 1968, now U.S. Pat. No. 3,447,741. It has been found, however, that even the presence of small amounts of excess free aldehyde compounds results in very serious difficulties in subsequent film processing steps. This problem is believed to be caused by a reaction under alkaline conditions between the excess free aldehyde compounds and some or all of the dye couplers present in the color emulsions, thereby destroying good color balance in the processed film.

One solution to this problem has been proposed in Blackmer et al., U.S. Pat. No. 3,168,400. This patent teaches that harmless addition products can be formed by reacting the excess free aldehyde compounds with primary amine compounds which have a hydroxyl, carbonyl or amino group attached to the primary amine radical. These primary amines, however, have proved to be relatively expensive, in addition these primary amine compounds are often in short supply and difficult to obtain.

SUMMARY OF THE INVENTION

The invention is the improvement comprising the use of bisulfite ion to remove excess free aldehyde compounds from photoprocessing solutions. These bisulfite ions react with any excess free aldehydes present to form addition products which are harmless from a photoprocessing point of view.

The use of bisulfite ions offers the advantages of making the removal of excess free aldehydes economically feasible, simple but reliable. Additionally, the use of bisulfite neutralizers allows the elimination of the heretofore used chemical fogging agent t-butylamine borane in rapid reversal color processes because the bisulfite itself will act as a chemical fogging agent. This offers several significant further advantages since t-butylamine borane is both expensive and toxic, and since aldehyde neutralization and chemical fogging can be carried out simultaneously.

DESCRIPTION OF THE PREFERRED EMBODIMENTS

There are many photoprocesses wherein aldehydes are used early in the processing sequence. In most of these, it is necessary and/or advantageous to remove any excess free aldehyde compounds before subsequent processing steps are initiated. This is particularly true in the processing of color films, because the free aldehydes react with certain dye formers present in the color emulsions. When this happens, it is virtually impossible to obtain good color balance in the processed film.

Some examples of aldehydes used in reversal color processing include: dialdehydes, especially glutaraldehydes such as glutaraldehyde; beta methylglutaraldehyde; alpha, alphadimethylglutaraldehyde; alphamethylglutaraldehyde; and alpha, beta dimethylglutaraldehyde; monoaldehydes such as succinaldehyde, formaldehyde; and combinations of these.

It has been found that excess free aldehyde compounds can be removed

It can be found that excess free aldehyde compounds can be removed by contacting the aldehydes with bisulfite ion. Bisulfite ion can be obtained from many sources, including but not limited to solutions of soluble sulfite compounds. Some

examples of such soluble sulfite compounds include: inorganic sulfites such as sodium sulfite; organic sulfites such as ethane disulfonic acid; metabisulfites such as sodium metabisulfite; and bisulfites such as sodium bisulfite. A preferred source of bisulfite ion is aqueous solutions of alkali metal bisulfites, especially sodium bisulfite.

When aqueous solutions of sulfites or metabisulfites are used, it is preferable to control the pH of the solution so that it is neutral or acidic so that adequate quantities of the bisulfite ion will be generated.

In general, the amount of bisulfite ion used will depend upon the amount of excess free aldehyde to be removed. To remove all of the excess free aldehyde, of course, will require that the bisulfite ion be added on a molar basis. Since the amounts of excess free aldehydes are usually low, normally from about 0.1 percent to about 10 percent of a bisulfite compound by weight dissolves in solution is adequate. Preferably, the amount is about 1 percent dissolved bisulfite compound.

The invention is further illustrated by the following examples.

EXAMPLE I

A strip of Ektachrome type 2448 film is exposed on an Eastman Kodak 1b sensitometer with a Corning 5900 daylight filter, to a 21-step carbon wedge for 1/25 second. After exposure the strip is processed with the following solutions:

Developer:	
Quadratros	2.0 g.
Phenidone	1.0 g.
Sodium Sulfite (anh)	50.0 g.
Methylhydroquinone	7.0 g.
Ethylenediamine (93%)	26.0 ml.
Sodium Thiocyanate	1.0 g.
Boric Acid	12.0 g.
Potassium Iodide (0.1% soln)	13.0 ml.
1-phenyl-2-tetrazoline-5-thione (0.5% soln)	5.0 ml.
Water to make	1.0 l.
Stop Bath:	
Sodium Sulfate	100.0 g.
Acetic Acid (glacial)	20.0 ml.
Sodium Acetate (3H ₂ O)	10.5 g.
Water to make	1.0 l.
Hardener:	
Glutaraldehyde (25% solution)	80 ml.
Sodium Sulfate (anhydrous)	100 g.
H ₂ O	1.0 l.
pH	4.0
Neutralizer:	
Sodium Bisulfite	5.0 g.
Water	15.0 ml.
Color Developer:	
Quadratros	0.28 g.
Benzyl Alcohol	7.5 g.
tert-butylamine borane	40.0 g.
Sodium Sulfite (anh)	0.9 g.
Sodium Phosphate (tribasic)	31.0 ml.
Sodium Bromide	3.6 g.
Potassium Iodide (0.1%)	13.0 g.
Citrazinic Acid	7.5 g.
4-amino-N-ethyl-N-(betamethanesulfonamidoethyl)-m-Toluidine, sesquisulfate monohydrate	1.0 l.
Sodium Hydroxide	12.0
H ₂ O	to
pH	
Clearing Bath:	
Potassium metabisulfite	40.0 g.
H ₂ O	1.0 l.
Bleach:	
Sodium Bromide	26.0 g.
Sodium Ferrocyanide 10H ₂ O	18.0 g.
Potassium Persulfate	51.0
Sodium Phosphate (dibasic anh)	12.5
Carbowax 1540 (50%)	6.0 ml.
H ₂ O	1.0 l.
pH	7.8
Fixer:	
Sodium Sulfite	10 g.
Sodium Thiosulfate (5H ₂ O)	250 g.
Ammonium Sulfate	50 g.
Stabilizer:	
Formalin Solution	10 ml.
X Ethylenediamine tetraacetic-acid (Tetra sodium salt)	11 10.0 g.

1.0 l. Water to make

The reversal processing sequence is:

Developer	75° F.	for 2 minutes
Stop Bath	75° F.	for 30 seconds
Hardener	100° F.	for 30 seconds
Neutralizer	100° F.	for 1 minute
Color Developer 100° F.	100° F.	for 8 minutes
Clear	100° F. for 30 seconds	
Bleach	120° F.	for 2 minutes
Fixer	120° F.	for 1 minute
Wash	120° F.	for 2 minutes

The sodium bisulfite neutralizer is used in amounts of 0.1 percent, 1.0 percent and 10.0 percent. In each case, excellent color balance is maintained in the processed film which indicates that the excess free aldehydes remaining in the film after the hardening step are neutralized.

EXAMPLE II

The film, exposure conditions, processing solutions and processing sequence are the same as in example I except that the neutralizer comprises a 10 percent aqueous solution of sodium metabisulfite ($Na_2S_2O_5$). The processed film displays excellent color balance.

EXAMPLE III

The film, exposure conditions, processing solutions and processing sequence are the same as in example I except that a 10 percent aqueous solution of sodium sulfite (Na_2SO_3) is used as the neutralizer. Two runs are made. The first at a neutralizer pH of seven results in a processed film with a maximum density in the magenta dye decreased 0.2 density units. The second run with the neutralizer pH adjusted to 3.1 with sulfuric acid results in a processed film having excellent color balance with no loss of density.

EXAMPLE IV

The film, exposure conditions, processing solutions and processing sequence are the same as in example I except that the neutralizer comprises a 5 percent aqueous solution of ethane disulfonic acid adjusted to a pH of 3.1 with sulfuric acid. The processed color film had excellent color balance.

EXAMPLE V

This example demonstrates the use of a bisulfite neutralizer to both remove excess free aldehydes and to chemically fog the silver halide remaining after first development.

The film and exposure conditions are the same as used in example I. The processing solutions are the same as used in example I except that the tert-butylamine borane is removed from the color developer. The processing sequence is as follows:

10	Developer	75° F.	for 2 minutes
	Stop Bath	75° F.	for 1 minute
	Hardener	100° F.	for 1 minute
	10% Sodium Metabisulfite	100° F.	for 1 minute
15	Water Rinse	100° F.	for 8 minutes
	Color Developer	100° F.	for 1 minute
	Clear	100° F.	for 4 minutes
	Bleach	100° F.	for 2 minutes
	Fixer	100° F.	for 5 minutes
	Wash	100° F.	

20 All operations are carried out in total darkness up to the bleach step to prevent fogging.

Sensitometric results and color balance are equivalent to those obtained in example I where a chemical fogging agent was present in the color developer.

25 Other embodiments will occur to those skilled in the art and are within the scope of the following claims.

What is claimed is:

1. In the reversal processing of color films, the improvement for removing excess free aldehyde compounds from the film 30 prior to color development comprising contacting said aldehyde compounds with bisulfite ion under neutral or acidic conditions.

2. The improvement of claim 1, wherein said aldehydes are contacted with a solution containing an inorganic bisulfite compound.

3. The improvement of claim 2 wherein said inorganic bisulfite compound is present as an aqueous solution containing between about 0.1 and about 10 percent bisulfite compound on a weight basis.

40 4. The improvement of claim 3 wherein said inorganic bisulfite compound comprises an alkali metal bisulfite compound.

5. The improvement of claim 4 wherein said inorganic bisulfite compound comprises sodium bisulfite.

UNITED STATES PATENT OFFICE
CERTIFICATE OF CORRECTION

Patent No. 3,634,081 Dated January 11, 1972

Inventor(s) Donald J. Forst

It is certified that error appears in the above-identified patent and that said Letters Patent are hereby corrected as shown below:

Col. 1, lines 16 and 17, delete "now U.S. Pat. No. 3,447,741." and insert therefor --- now abandoned. ---;

Col. 1, lines 70 and 71, delete the following sentence, "It has been found that excess free aldehyde compounds can be removed.";

Col. 1, line 72, cancel between the words "It" and "found" the words "can be" and insert the words --- has been ---;

Col. 2, line 76, delete "X" before the words "Ethylenediamine tetraacetic-acid" and change "11 10.0 g." (second column) to --- 10.0 g. ---;

Col. 3, line 2, delete "1.01." and insert in line 1, second column therefor --- 1.0 liter. ---;

Col. 3, line 8, in the first column after "Color Developer", move "100°F." to the second column.

Signed and sealed this 4th day of July 1972.
